DEVICE FOR EXERCISING ORTHOPEDICALLY AND MASSAGING THE UNSHOD HUMAN FOOT

Leo Blumenthal, Berlin-Charlottenburg,
GermanyApplication November 13, 1935, Serial No. 49,615
In Germany July 28, 1933

8 Claims. (Cl. 128—69)

This invention refers to a device for exercising orthopedically and massaging the unshod human foot.

It consists of a mattress or a mat partially filled 5 with gravel or similar coarse material mixed with finer material. Mattresses filled with powdered soap stone, which is capable of retaining and storing considerable quantities of heat, have been used before now for medical purposes and for 10 treating the feet of patients by means of heat.

The object of this present invention is to exercise and massage the unshod human foot and give to it that activity which a human being would get in running barefoot on rough unpaved ground 15 in free nature.

This invention makes it possible in a very simple manner to reproduce the natural conditions of rough ground in stimulating the foot to strongly arch itself away from the irritating lumpiness and 20 angularities of such a surface, and to give to the growing child, at all times of the year, and in the house, the opportunity of developing the muscles of its feet in the proper way. In accordance with this invention a container made of pliable, 25 washable material shaped like a mattress or a mat and large enough to form a running track for a child or a patient, is partly filled with gravel, broken stones, or some similar coarse, hard and lumpy material, with which finer material may 30 be mixed. The filling of the container should not be tightly packed, so that when walking over this mattress the filling of the same can yield to assume fresh surface configurations and the foot is forced to arch itself to the irregularities of the 35 surface of the mattress and to grip it and this massages the foot and stimulates it to arch itself in the same way as would occur when running over rough ground. The mat may be divided into squares each of which is filled with this material 40 to an extent permitting this yielding of the surface configuration. The filling may be only coarse gravel or similar material, which in itself is unyielding, hard, and lumpy, and to it may be added sand, sawdust, horse-hair, sea-weed, 45 fucus or other pliable material for the purpose of moderating the stimulating or irritating action of the hard, lumpy, gravelly material on the sole of the foot. Sand alone is not suitable because it is a poor conductor of heat and might lead to 50 chills. Also it is not adapted to stimulate an arching action of the foot. The filling must be such as to yield easily and not ball together inside the container. The mattress may be made so that it is easily transported and is light in 55 weight. This foot exercising mattress may be

used for quite young babies and the coarseness or hardness of the surface may be temporarily reduced by putting a blanket over the mattress.

An embodiment of the invention is shown in the accompanying drawing, in which

Fig. 1 is a cross-sectional view and

Fig. 2 is a plan view of a mattress or mat filled with coarse and fine material.

Fig. 3 is a partial cross-sectional view on a larger scale.

1 denotes the outer cover of the mat and 2 denotes a blanket or the like which can be easily removed and washed. 3 is the filling which, as indicated in Fig. 3, in this case consists of mixed coarse and fine material. The mat is by means 15 of longitudinal and transverse seams divided in a plurality of parts or pockets 4.

I claim:—

1. A device for orthopedically exercising and massaging the unshod human foot, comprising 20 a mat capable of forming a walking or running track for the patient and having a filling of bodies of such shapes that the friction between the bodies prevents a smooth sliding of the same over each other so that the mat presents a lumpy gravelly surface simulating rough unpaved ground in stimulating an arching action of the feet of the patient thereon.

2. A device according to claim 1 in which the mat comprises an envelope and in which the filling is packed somewhat loosely in the envelope to permit yielding of such material in the envelope and consequent changing of the irregular surface configuration of the mat.

3. A device according to claim 1, in which the mat comprises an envelope and in which the filling is packed somewhat loosely in the envelope in combination with a finer material to permit yielding of said material in the envelope and consequent changing of the irregular surface configuration of the mat.

4. A device according to claim 1, in which the mat comprises an envelope subdivided into pockets containing the filling packed somewhat loosely therein to permit yielding of said bodies in the envelope and consequent changing of the irregular surface configuration of the mat.

5. A device according to claim 1, in which the mat comprises an envelope subdivided into pockets containing the filling and in which the bodies are mixed with a finer material both packed somewhat loosely in the envelope to permit yielding of said material in the envelope and consequent changing of the irregular surface configuration of the mat.

6. A device according to claim 1, in which the mat comprises an envelope containing the filling and in which the bodies are mixed with saw-dust, sand, horse hair, or other fine material packed somewhat loosely in the envelope to permit yielding of said material in the envelope and consequent changing of the irregular surface configuration of the mat.

7. A device according to claim 1, in which the mat comprises an envelope subdivided into pock-

ets containing the filling and in which the bodies are mixed with saw-dust both packed somewhat loosely in the envelope to permit yielding of said material in the envelope and consequent changing of the irregular surface configuration of the mat. 5

8. A device according to claim 1, in which the bodies are irregularly shaped.

LEO BLUMENTHAL. 10
